UNITED STATES PATENT OFFICE.

GEORGE C. VAN RODEN, OF PHILADELPHIA, PENNSYLVANIA, ASSIGNOR TO
J. E. CALDWELL & COMPANY, OF PHILADELPHIA, PENNSYLVANIA.

DESIGN FOR A PENDENT PIN.

SPECIFICATION forming part of Design No. 35,991, dated August 12, 1902.

Application filed December 14, 1901. Serial No. 85,992. Term of patent 14 years.

To all whom it may concern:

Be it known that I, GEORGE C. VAN RODEN, a citizen of the United States, residing in Philadelphia, Pennsylvania, have invented and produced a certain new, original, and ornamental Design for a Pendent Pin, of which the following is a specification.

My design for a pendent pin is fully illustrated in the accompanying drawings, in which—

Figure 1 represents a face view of the pin, and Fig. 2 is a side view.

The essential feature of the design is a pendent pin representing a distaff and a ribbon.

A is the representation of a distaff of a

spinning-wheel having a body portion *a* and curved extensions *a'*, terminating in a point *a''*. Extending from this point to the opposite end and covering part of the distaff is a ribbon name-plate B in the form of a scroll.

I claim—

The ornamental design for a pin as herein described and as illustrated in the accompanying drawings.

In testimony whereof I have signed my name to this specification in the presence of two subscribing witnesses.

GEO. C. VAN RODEN.
